CLAIM

The ornamental design for an integrated light head, as shown and described.

DESCRIPTION

FIG. 1 is a perspective view showing the front of the integrated light head of the present invention.

FIG. 2 is a side view of the integrated light head.

FIG. 3 is a front view of the integrated light head.

FIG. 4 is bottom plan view of the integrated light head.

FIG. 5 is a back view of the integrated light head.

FIG. 6 is a top plan view of the integrated light head; and,

FIG. 7 is another side view of the integrated light head.

The broken lines shown are included for the purpose of illustrating environmental structure and form no part of the claimed design.

The present invention involves an ornamental design of a light head that combines softbox connectors with a parabolic head. In particular, the light head has a parabolic head integrated with softbox connectors used for connecting, e.g., a standard rectangular softbox, a strip softbox or an octagonal softbox. The parabolic head is partially formed from a concave or bowl-like shape base, and has an opening for receiving the bulb socket of a power source. Softbox connectors are integrated and placed on the outside edge or circumference of the parabolic head. The connectors are protrusions having a recess, on one or more faces of the protrusion, for receiving ends of a softbox frame member. The shape of a connector complements the frame member used to secure the photographic accessory. The integration of the connectors and parabolic head provides a unique ornamental light head design.
